UNITED STATES PATENT OFFICE.

JOHN F. O'CONNOR, OF CHICAGO, ILLINOIS, ASSIGNOR TO WILLIAM H. MINER, OF CHAZY, NEW YORK.

RAILWAY DRAFT-RIGGING.

1,223,823.

Specification of Letters Patent. Patented Apr. 24, 1917.

Application filed March 18, 1915. Serial No. 15,345.

To all whom it may concern:

Be it known that I, JOHN F. O'CONNOR, a citizen of the United States, residing at Chicago in the county of Cook and State 5 of Illinois, have invented a certain new and useful Improvement in Railway Draft-Rigging, of which the following is a full, clear, concise, and exact description, reference being had to the accompanying drawings, 10 forming a part of this specification.

This invention relates to improvements in railway draft riggings.

An object of the invention is to provide a high capacity friction gear for railway car 15 draft riggings and one in which the release is always certain.

Another object of the invention is to provide a friction gear for railway draft riggings employing wedging or spreading 20 means consisting of a main wedge or spreader and auxiliary wedges or spreaders interposed between the main wedge and the friction shoes.

The invention furthermore consists in the 25 improvements in the parts and devices and in the novel combinations of the parts and devices, as herein shown, described or claimed.

In the drawing forming a part of this 30 specification, Figure 1 is a vertical longitudinal sectional view of a draft rigging embodying my improvements, the yoke being shown in side elevation. Fig. 2 is an enlarged detail sectional view of the frictional 35 elements proper showing the position of the parts in full release and Fig. 3 is a view similar to Fig. 2 showing the position of the frictional elements under full buff. Fig. 4 is an enlarged vertical sectional view taken 40 substantially on the line 4—4 of Fig. 1 and Fig. 5 is a detail, perspective view of one of the auxiliary wedges.

In said drawing, 10 denotes the center sills, 11 the rear stop, 12 the front stop, 13 the rear follower, 14 the front follower, 15 the draw-bar, 16 the yoke and 17 the key connecting the yoke and draw-bar. All the aforementioned parts are or may be of any well known construction.

The gear proper, as shown, comprises a 50 casting having a friction shell portion 170 and spring case or chamber 18. Mounted in the chamber 18 is a spring which comprises an inner coil 19 and outer coil 20 both of which bear at their rear ends against integral wall portions 21 of the combined friction shell and spring casing. Mounted within the friction shell 17 which, as shown most clearly in Fig. 4, is substantially rectangular in cross section, are upper and lower friction shoes 22—22 each of which on its inner face is provided with a pair of inclined anti-friction roller seats 23—23. Located in said roller seats are anti-friction rollers 24—24, the normal position of which is as most 60 clearly shown in Fig. 2. These rollers 24 also roll in suitable inclined roller bearing seats 25 formed on the outer faces of auxiliary wedges 26, each of said auxiliary wedges 26 having its outer end 27 inwardly 65 inclined toward the axis of the gear (see Figs. 1 and 2). Mounted between the auxiliary wedges 26 is a double faced main wedge 28, the latter at its inner end bearing against a spring follower 29. Interposed between the wedging faces of the main wedge 28 and the inner faces of the auxiliary wedges 26 are anti-friction rollers 30, each of which is seated in a recess 31 having an inclined bottom formed on the inner faces 70 of the auxiliary wedges 26. Interposed between the auxiliary wedges 26 and the front follower 14 is a block 32 having its inner face inclined as indicated at 33 and which corresponds to the inclined ends 27 75 of the auxiliary wedges. The shape and size of the block 32 is such that upon inward movement thereof it will move inside of and clear the shoes 22. A retaining bolt 34 is provided which extends through the block 80 32, main wedge 28, spring follower 29, springs and rear wall 21 of the friction shell, said bolt holding the parts in assembled position and the springs under an initial compression.

The operation of the device is as follows: Under buff, the front follower 14 is moved inwardly by the draw-bar and this in turn

forces the block 32 and auxiliary wedges 26 inwardly until such time as the front follower 14 comes into engagement with the outer ends of the friction shoes 22, it being understood that the latter remain stationary during this initial portion of the action of the gear. During the operation just described, the auxiliary wedges 26 not only travel longitudinally of the gear but move inwardly, due to the anti-friction rollers 24 rolling up the inclined pockets 23 therefor. Also the auxiliary wedges 26 in traveling inwardly along the inclined faces 38 of the block 32 are caused to move axially of the gear at a faster rate than that of the follower. This in turn gives the main wedge 28 an increased lineal speed. After the follower 14 has come into engagement with the ends of the friction shoes, the latter are then, of course, forced inwardly with the follower and resistance is created by the spring through the medium of the main and auxiliary wedges, the ultimate movement occurring when the follower 14 engages the end of the friction shell. Upon release, the friction shoes remain stationary during the initial portion thereof, while the main wedge, auxiliary wedges and block 32 are moved outwardly, thus perfectly releasing the gear, until the spring follower plate 29 engages the friction shoes. During the remaining portion of the release action, the wedges and friction shoes move outwardly as a unit. While the preceding description relates more particularly to action under buff, it is apparent that the same sequence of operations takes place under draft, the only difference being that it is the friction shell which is moved instead of the front follower. It will be noted that a spring pressure is transmitted directly to the friction shoes through the wedging means and consequently the resistance to the shoe movements is uniformly graduated since it is dependent upon the amount of compression of the spring and on account of the novel releasing features, the angles of thrust may be varied.

Although I have herein shown and described what I now consider the preferable form of my invention, yet it will be understood that various changes may be made, such for instance as in the shape of the shell, the number and arrangement of the friction shoes, etc., without departing from the spirit of the invention and all such changes and modifications are contemplated as come within the scope of the claims appended hereto.

I claim:

1. A friction gear for draft riggings comprising a friction shell, friction shoes, a spring, a main wedge acting directly against said spring, auxiliary wedges between the

main wedge and shoes, and anti-friction rollers between the auxiliary wedges and shoes, said shoes remaining stationary during initial portions of the actuation of the gear.

2. A friction gear for draft riggings comprising a friction shell, friction shoes co-operable therewith, a spring; a main wedge, auxiliary wedges between the main wedge and shoes, and a plurality of anti-friction rollers between each shoe and its corresponding auxiliary wedge, said shoes remaining stationary during initial portions of the actuation of the gear.

3. A friction gear for draft riggings comprising a friction shell, friction shoes co-operable therewith, a spring, wedging means interposed between said spring and shoes and including a main and auxiliary wedges, and anti-friction rollers between the main and auxiliary wedges and also between the auxiliary wedges and the friction shoes.

4. A friction gear for draft riggings comprising a friction shell, friction shoes co-operable therewith, a spring, wedging means interposed between said spring and shoes and including a main and auxiliary wedges, and anti-friction rollers between the main and auxiliary wedges and also between the auxiliary wedges and the friction shoes, there being a plurality of anti-friction rollers between each auxiliary wedge and adjacent friction shoe.

5. A friction gear for draft riggings comprising a friction shell, friction shoes co-operable therewith, a spring, a main wedge, auxiliary wedges interposed between the main wedge and the friction shoes, and anti-friction rollers interposed between the friction shoes and auxiliary wedges, said friction shoes and auxiliary wedges having roller bearing faces inclined inwardly toward the center of the gear to thereby cause the auxiliary wedges to move inwardly toward the axis of the gear during initial portions of buff and draft actions, said shoes remaining stationary during said initial portions of buff or draft actions.

6. A friction gear for draft riggings comprising a friction shell, friction shoes, a spring, a main wedge, auxiliary wedges, a plurality of anti-friction rollers between each shoe and corresponding auxiliary wedge, a follower, and a block interposed between the follower and the auxiliary wedges, the latter and said block having inclined engaging faces.

7. A friction gear for draft riggings comprising a friction shell, friction shoes co-operable therewith and having their outer ends extended beyond the end of the friction shell, a spring, wedging means interposed between said spring and shoes and including a main wedge and auxiliary wedges,

a plurality of anti-friction rollers between the friction shoes and auxiliary wedges and between the auxiliary wedges and the main wedge, a follower normally spaced from the outer ends of said friction shoes, and means for transmitting pressure from said follower to the auxiliary wedges independ-

ently of the friction shoes during initial actions of the gear.
